DRAINAGE RECEPTACLE

Filed May 29, 1935

Fig. 2.

UNITED STATES PATENT OFFICE

2,030,708

DRAINAGE RECEPTACLE

Courtney N. Mitchell, Strongsville, Ohio

Application May 29, 1935, Serial No. 23,976

12 Claims. (Cl. 4—290)

This invention relates, as indicated, to drainage receptacles and particularly to those intended for the reception and drainage of refuse, especially garbage which accumulates at the ordinary kitchen sink. Heretofore, such receptacles have been provided with means for draining the water usually present in the refuse deposited in them, but have not been provided with any means for regulating this drainage or stopping it entirely. 5 when it was desired to move the receptacle from one place to another, such as in transporting it from the kitchen sink to an incinerator or to a larger receptacle. It may be used for numerous other purposes than for the reception of refuse. 10 In modified form it is adaptable for use in the fruit and vegetable preserving business, in the chemical industry and in many other lines of manufacturing and merchandising.

The chief object of this invention is to provide 20 means for automatically stopping the drainage of a receptacle when the receptacle is moved from one place to another. Another object is to provide means for regulating the rate of drainage of the receptacle. Another object is to provide a 25 device of this character which is convenient to handle and one which can be adapted readily to the space which it is intended to occupy. A still further object is to provide a device of this character which can be readily disassembled for 30 cleaning and for the replacement of parts. Another object is to provide a drainage receptacle which is adapted to be coated readily with a protective covering. An additional object is to provide a receptacle which may be manufactured 35 rapidly and at low cost and with a small number of dies and other tools.

With these and other objects in view which will appear as the description proceeds, said invention then consists of the means hereinafter 40 fully described with reference to the accompanying drawing and more particularly pointed out in the appended claims.

In said accompanying drawing Fig. 1 is a plan view of the improved drainage receptacle. Fig. 2 45 is a section substantially on line 2—2 of Fig. 1. Fig. 3 is a fragmentary section similar to a part of Fig. 2, but showing a modified form of the supporting pad and valve.

Referring now to the constructional details as 50 shown by the drawing, the basin 10 which is usually provided with an outwardly projecting flange or a bead at 11, contains a floating false bottom 12 which may be made from a suitable screen or a perforated plate having holes 13 55 through which liquid may drain. This false bot-

tom is supported on the pads 14 attached thereto by screws or rivets 15 or the pads may be vulcanized to the false bottom when the pads are made of soft rubber which is the material usually employed in their construction. 5

The pads 14 are provided with an enlarged end 16 which after the assembly of the pad to the false bottom is forced through the hole in the bottom of basin 10 provided for its reception. The lower part of pad 14 is made in a substantially U form permitting it to compress or collapse to facilitate its assembly into the hole in the bottom of the basin 10 and to provide a passage for the liquid which has passed through holes 13 into space 17 below the false bottom. 10 The diameter of the neck 18 of the pad is such as to have a free fit in the hole through which it passes. At the upper part of the pad is the flexible flange or valve member 19 which engages the edges of the hole in the bottom of the basin 20 in sealing relationship when the pad is permitted to drop downward under the force of a load of material supported on the false bottom. This will then occupy the position as shown at 20 in Fig. 2, thus preventing the flow of any liquid 15 from the space 17 through the passages 21 in the pads. The edges of the holes in the bottom of the basin 10 may be formed as shown at 22 to facilitate both assembly and the sealing action of the flange valve. In the absence of other 25 means to engage a supporting surface as represented by the line 23, the shoulder 24 will engage the edges of the holes and the basin and false bottom will be supported with a substantial space between them as shown in the left hand 30 portion of Fig. 2. When the basin is elevated, the weight of the false bottom itself enhanced by that of any draining material carried thereon 35 will cause the valve flange 19 to seat as at 20 in the right hand part of Fig. 2, thus preventing 40 any flow from space 17 through the spaces 21 in the pads 14.

When it is desired to regulate the flow of liquid 45 from the space 17, the adjustable supports 25 are provided to engage the supporting surface 45 represented by the line 23. The head 26 of the screw 27 then rests on the surface 23 and pads 14 are prevented from rising and fully opening 50 the flange valves 19. By adjusting the position of supporting screws 27, which are threaded into bosses 28 and locked with nuts 29, the amount of opening of the valves is regulated and the flow therethrough is retarded. The bosses 28 are provided by tapping and cutting off sec- 55

tions of round bars and welding them to the bottom of the basin 10.

In the usual construction three supporting pads and valves are employed as shown on the drawing in order that all valves seat evenly and simultaneously. The flexible structure of the valves provides for this condition. However, a large single valve centrally located may be employed to advantage in some modifications of this receptacle. On the other hand, when a greater rate of drainage is desired a large number may be employed by exercising care in assembly so that all valves may be closed simultaneously.

To provide for the sealing of the valves when irregularities occur in the spacing of the holes in the bottom of the basin 10, or in the locations of the supports for the valves in the false bottom 12, the construction shown in Fig. 3 is employed.

In this the rod 29 having its lower end enlarged and knurled or otherwise prepared to be permanently secured in the support pad 30, has its upper end formed in the shape of a sphere. This spherical end 31 is held with suitable self aligning pressure between a spherical seat 32 in the false bottom 33 by means of spherically formed washer 34, the latter being welded or riveted to the false bottom. The supporting pad 30 has a spherically formed seating flange 35 adapted to engage the seat 36 in the bottom of the basin 37. Slots 38 are provided in the pad as free passages for liquid from the space 39 and as means for collapsing the enlarged portion in removing the pad 30 from the opening in the bottom of the basin. The interior portion of the support pad is removed to increase the flexibility of the attachment of rod 29.

In some cases the hinged support 40 is employed instead of the adjustable screws 26 which provides a fast and easy method of removing the supports or in providing a support readily adjustable for two different heights. The hinged support 40 is constructed to rotate about the center of the shaft 41 which is carried by a bracket 42. This bracket is made of resilient material, preferably of spring steel having its ends 43 secured to the bottom of the receptacle 10, usually by welding. The support 40 having flat sides and a slightly rounded corner at 44 deflects the bracket when turned on its axis and the tension of the bracket holds the flat side of the support firmly against the bottom of the receptacle keeping the support in its upright position as shown in full lines and holding it in the horizontal position when turned as shown by the broken lines.

To prevent corrosion of the parts entering into the construction of this receptacle, their surfaces are treated to correspond with the conditions which they must resist. Among these are various metal plating coverings, enameling, rubber and other materials applied electrolytically, by spraying and by other processes.

It will be evident from the foregoing that this receptacle can be inverted for the purpose of emptying it or for other purposes without the false bottom becoming disengaged from the bottom of the basin and that water or air can be flushed through the passages in the supporting pads for cleaning the space between the false bottom and the bottom of the basin. Furthermore, for the purpose of thoroughly cleaning all parts, the pads may be compressed from underneath the basin and forced through their respective openings in the bottom of the basin and the false bottom assembly removed in its entirety.

The pads are of such form relative to the openings that the false bottom can be reassembled by pressing it down forcing the pads through the curved edged openings, the assembly being facilitated by lubricating the surfaces passing through the openings by means of water or oil.

The false bottom is formed to fit into the bottom of the basin with whatever clearance is needed for the thickness of the edges of the valves, and the contour of the false bottom is such as to enter the basin with suitable clearance to insure easy assembly and disassembly, but with small enough clearance to prevent particles from passing into the space under the false bottom which would interfere with the seating of the valves. It is to be noted that the general form of the false bottom corresponds with the form of the bottom of the basin and that the forming dies used in the manufacture of one of these parts may be employed, at least in part, in the making of the other.

The basin 10 may be made in approximate triangular form to fit into a square corner or in a variety of other forms such as in hexagonal form to economize space when several such receptacles are to be placed adjacent to each other. Numerous other modifications may be made in the various details, especially in regard to the form of the supporting pads 14 which, as hereinbefore explained, serve as valves to prevent leakage from space 17. These may be made of metal, such as stainless steel, and with spherical portions to engage spherical formed seats in the bottom of the receptacle. These valves and valve seats may be lapped or ground to prevent leaks, or they may have leather or rubber facings to provide the sealing required. When made of rubber as shown, or other flexible and impervious material, they may be modified in form to serve as vacuum cups to hold the receptacle in place on the surface represented by the line 23.

Numerous other modes of applying the principle of my invention may be employed instead of the one explained, change being made as regards the mechanism herein disclosed, provided the means stated by any of the following claims or the equivalent of such stated means be employed.

I therefore, particularly point out and distinctly claim as my invention:

1. In a drainage receptacle, the combination of a basin having an opening in its bottom, a plate adapted to fit into said basin in proximity with the bottom, and a plug attached to said plate and passing loosely through the opening in the bottom of the basin.

2. In a drainage receptacle, the combination of a basin having an opening in its bottom, a plate adapted to fit into said basin in proximity with the bottom, a plug attached to said plate and passing loosely through the opening in the bottom of the basin, and a drain passage in said plug.

3. In a drainage receptacle, the combination of a basin having an opening in its bottom, a plate adapted to fit into said basin in proximity with its bottom, a plug attached to said plate and passing loosely through the opening in the bottom of the basin, and an enlarged portion on said plug exteriorly of the basin.

4. In an article of the class described, the combination of a basin having a bottom wall and a side wall, an opening in one of the walls, a member adapted to fit into said basin in proximity with the opening, a plug attached to said member

and passing loosely through said opening, and means adapted to permit the removal of said plug from said opening.

5. In an article of the class described, the combination of a basin having a bottom wall and a side wall, an opening in one of said walls, a member adapted to fit into said basin in proximity with the opening, a plug attached to said member and passing through said opening, and a drainage 10 passage in said plug.

6. In an article of the class described, the combination of a basin having a bottom wall and a side wall, an opening in one of said walls, a member adapted to fit into said basin in proximity 15 with the opening, a plug attached to said member and passing through said opening, a passage in said plug, and means provided in said plug for collapsing the same whereby the said plug may be removed from said opening.

20 7. In an article of the class described, the combination of a basin having a bottom wall and a side wall, an opening in one of said walls, a member adapted to fit into said basin in proximity with the opening, a plug attached to said member and 25 passing through said opening, and means provided in said plug whereby the same may be collapsed for removing the plug from the opening.

8. In an article of the class described, the combination of a basin having a bottom wall and a side wall, an opening in one of said walls, a member adapted to fit into said basin, a valve attached 30

to said member and adapted to close said opening, and means associated with said valve adapted to move said valve relative to said opening.

9. In an article of the class described, the combination of a basin having a bottom wall and a side wall, an opening in one of said walls, a plug passing through said opening, said plug comprising a valve adapted to close said opening, means associated with said plug adapted to close said valve when said basin is moved relative to a supporting surface on which said basin may rest. 10

10. In a drainage receptacle, an inner member and an outer member, a valve attached to one of said members and adapted to close an opening in the other of said members, and means associated with said valve to permit said valve to close when one of said members is moved relative to its supporting means. 15

11. In a drainage receptacle, an inner member and an outer member, a valve attached to one 20 of said members and adapted to close an opening, and a support attached to one of said members, the said support being adapted to limit the movement of said valve.

12. In a drainage receptacle, an inner member and an outer member, a valve attached to one 25 of said members and adapted to close an opening, and an adjustable support attached to one of said members, said support being adapted to limit the movement of said valve. 30
